BEACON AERIAL

Kurt Fränz, Berlin, Germany, assignor to Telefunken Gesellschaft für Drahtlose Telegraphie m. b. H., Berlin, Germany, a corporation of Germany

Application December 31, 1937, Serial No. 182,675
In Germany December 22, 1936

7 Claims. (Cl. 250—11)

This invention deals with the reduction of the horizontal component of field in the radio beacon course of a radio range.

The problem arises quite frequently in practice where beacon aerials have to be erected upon metallic surfaces of finite dimensions. For instance, the problem may consist in erecting or rigging up a radio range aerial upon the roof or top of a vehicle or to build a radio range equipment on the roof of a building. Because of the finite dimension of the base surface or ground sheet, standing waves arise thereon, and these result in a horizontal component in the field intensity. In the construction of ultra-short-wave beacons known in the art comprising two key-modulated reflector dipoles in an arrangement presenting mirror-image relationship to the guide beam or radio beacon course, the two horizontal components of the two side diagrams present a phase shift in reference to each other according to whether the right-hand or the left-hand reflector is closed, that is, elliptically polarized waves occur in each of the two side diagrams by virtue of reflection relative to the vertical plane of symmetry which contains also the guide beam. The example consisting of the simplest receiving antenna, that is, the vertical dipole, may be cited to prove that, in the presence of an inclination of the dipole, the radio beacon course or guide beam apparently shifts, and it is evident that consequently an airplane flying along curves and fitted with an antenna being perfectly vertically polarized in horizontal flying position would experience a corresponding shift of the guide beam as a function of its flying position. As a matter of fact, the aircraft, for the reception of radiations from a beacon station, has an antenna subject to more complicated polarization as a result of its metallic masses, etc., and this also results in a shift of the guide beam in a way as indicated.

The present invention will be more clearly understood by reference to the following detailed description, which is accompanied by a drawing, in which Figure 1 is a vector diagram explanatory of my invention, Figure 2 is a plan view of an embodiment of my invention, while Figures 3, 4 and 5 are elevational views of modifications of my invention.

The assumption is made that the beacon antenna radiates waves subject to linear polarization. Fig. 1 illustrates the situation in a plane of symmetry containing the guide beam. In this plane, the vertical components V_1 and V_2 of the two side diagrams are in agreement, and this is

true also, in so far as size or quantity is concerned, of the horizontal components H_1 and H_2 , though the horizontal components because of reflection are displaced in phase an angle of 180 degrees. At this point, therefore, the guide beam will be found with an antenna subject to purely vertical polarization. If, now, the receiving dipole is turned about a horizontal axis, the result is that for one of the side diagrams it will fall more in the direction of the resultant R_1 or R_2 of the two field intensity components, and for the other side diagram farther away from this direction. In other words, with such a receiver antenna the guide beam would no longer be located in the plane of symmetry, but laterally thereto in another plane in which the resultants, so far as their absolute values are concerned, will no longer be alike.

Now, according to the invention the undesired horizontal component is compensated in the radio beacon course and optionally also in other directions at least diminished by the aid of a supplementary radiation presenting predominantly horizontal polarization. This supplementary radiation may be produced by exciting, together with the others, one or more auxiliary radiators mounted at suitable points, the excitation being at the frequency and rate of the keying of the beacon, it being immaterial so far as the basic idea of the invention is concerned whether such excitation is obtained by means of radiation coupling or in a direct manner or by direct supply or feed. However, the auxiliary radiators should preferably be disposed symmetrically in reference to the radio beacon course plane.

An illustrative embodiment of the invention is shown in Fig. 2. On a base area F , assumed to be rectangular, is mounted in the center the energy-fed vertical rod A , while laterally in reference thereto are mounted the two key-modulated reflector rods R_1 and R_2 . The guide beam will then be in a position at right angles to the line connecting the three rods. Practical experience has shown that the relationship between the vertical component and the horizontal component in the radio beacon course or guide beam will still be as 10:1, in such an arrangement, if the base area is roughly equal to one-half the length of the operating wave in width and length. If the base area could be enlarged at will, it will be seen that the horizontal component finally would disappear. An arrangement according to the invention would be, for instance, if in lieu of this inconvenience the shape of the horizontal base area were formed in

such a way, say, by the provision of extensions, etc., that the horizontal component in the direction of the beacon course is diminished. In the exemplified embodiment Fig. 2 two horizontal bars H_1 and H_2 of suitable length have been added.

In the illustrative embodiment Fig. 3, there is connected with each of the reflector dipoles R_1 and R_2 a small horizontal radiator as indicated 10 at H_1 and H_2 , respectively, with phase shifting means P_1 and P_2 , respectively, being provided at the junction point. The said phase shifters and the length of the auxiliary horizontal bars should be so chosen that in the beacon course the field 15 intensity diagram of the horizontal component attains a minimum value. By varying the size and the phase of the additional or auxiliary component it will always be possible, at least in one direction, for example, in the beacon course or 20 guide beam, to absolutely secure perfect compensation of the horizontal component. The contact members T_1 and T_2 , Fig. 3, represent the reversing switch means for the reflector dipoles.

In Fig. 4 is shown an exemplified embodiment 25 in which the compensation of the horizontal component is obtained by radiation-coupled auxiliary radiators H_1 and H_2 , while the embodiment of Fig. 5 comprises energy-fed radiators which are associated with the same feeder lead S as the 30 chief radiator, and which, if desired, may be keyed alternately. Also in this organization phase shifting means may be included as shown in Figure 3.

I claim:

35 1. In a beacon antenna system comprising a vertical radiating system for radiating a vertically polarized beam of radiant energy, said radiating system being mounted on a ground sheet of finite area whereby a horizontally polarized component of said beam is produced, the method of compensating for the distortion in said beam resulting therefrom which comprises radiating an auxiliary horizontally polarized wave of such amplitude and phase that said horizontally polarized component is neutralized.

40 2. A beacon antenna system comprising a vertical radiating system for radiating a vertically polarized beam, said radiating system being mounted on a ground sheet of finite area whereby a horizontally polarized component of said beam is produced and means for radiating a horizontally polarized wave of such amplitude and phase that the said horizontally polarized component is neutralized.

45 3. A beacon antenna system comprising a vertical radiating system for radiating a vertically

polarized beam, said radiating system being mounted on a ground sheet of finite area whereby a horizontally polarized component of said beam is produced and means for radiating a horizontally polarized wave of such amplitude and phase 5 that the said horizontally polarized component is neutralized in the direction of said beam.

4. A beacon antenna system comprising a vertical radiating system for radiating a vertically polarized beam, said radiating system being 10 mounted on a ground sheet of finite area whereby a horizontally polarized component of said beam is produced and means for radiating a horizontally polarized wave of such amplitude and phase 15 that the said horizontally polarized component is neutralized, said means comprising a plurality of horizontal conductors disposed in a vertical plane passing through said radiating system and at right angles to said beam.

5. A beacon antenna system comprising a vertical radiating system for radiating a vertically polarized beam, said radiating system being 20 mounted on a ground sheet of finite area whereby a horizontally polarized component of said beam is produced and means for radiating a horizontally polarized wave of such amplitude and phase 25 that the said horizontally polarized component is neutralized, said means comprising a plurality of horizontal conductors disposed in a vertical plane passing through said radiating system and at 30 right angles to said beam and means for energizing said conductors.

6. A beacon antenna system comprising a vertical radiating system for radiating a vertically polarized beam, said radiating system being 35 mounted on a ground sheet of finite area whereby a horizontally polarized component of said beam is produced and means for radiating a horizontally polarized wave of such amplitude and phase 40 that the said horizontally polarized component is neutralized, said means comprising a plurality of horizontal parasitic radiators disposed in a plane passing through said radiating system and at right angles to said beam.

7. A beacon antenna system comprising a vertical radiating system for radiating a vertically polarized beam, said radiating system being 45 mounted on a ground sheet of finite area whereby a horizontally polarized component of said beam is produced and a plurality of horizontal conductors disposed in a plane passing through said radiating system at right angles to said beam and 50 means for energizing said conductors with a wave of such amplitude and phase that the horizontally polarized component of said beam is neutralized. 55
